UNITED STATES PATENT OFFICE.

HENRY V. FARIES, OF INDIANAPOLIS, INDIANA.

IMPROVEMENT IN PIPE-WRENCHES.

Specification forming part of Letters Patent No. 36,289, dated August 26, 1862.

To all whom it may concern:

Be it known that I, HENRY V. FARIES, of Indianapolis, in the county of Marion and State of Indiana, have invented a new and Improved Wrench for Grasping and Turning Gas-Pipes, Bolts, and any article of cylindrical form; and I do hereby declare that the following is a full, clear, and exact description of the same, reference being had to the accompanying drawings, making a part of this specification, in which—

Figure 1 is a side view of my invention. Fig. 2 is an edge view of the same.

Similar letters of reference indicate corresponding parts in the two figures.

This invention consists in having a jaw of hook form connected by a pivot to a rigid or stationary jaw at the end of a handle or lever, the hook-jaw extending over the face of the rigid jaw and all arranged, as hereinafter fully shown and described, whereby the implement, when applied to its work, will grasp the article to be turned firmly and adjust itself to its size or diameter without any special manipulation on the part of the operator, and at the same time by the ordinary manipulation of the implement release itself at each backward turn in order to admit of a fresh hold or grip being taken.

To enable those skilled in the art to fully understand and construct my invention, I will proceed to describe it.

A represents a handle or lever, which may be of any suitable length, and having at one end of it a jaw, B, formed by having a piece of steel of a requisite width welded to the handle or lever with its outer or face side of segment or slightly convex form, as shown clearly in Fig. 1. The face or convex surface of this jaw B is toothed or corrugated, as shown in Fig. 1 at a.

C represents a steel jaw of hook form, one end of which is provided with a tang, b, fitted in a slot, c, in the back part of the jaw B, and secured therein by a pivot, d, on which the tang b is allowed to turn or work freely.

The free or disengaged end of the jaw C projects over the front end of the jaw B, and the face side of the former has quite a quick bend or turn, forming nearly a right angle, as shown at e in Fig. 1.

D is a spring, which may be constructed of a flat steel plate. The lower or inner end of this spring is attached to the back part of the jaw B, and its outer end bears upon the back part of the jaw C and has a tendency to keep the same against the face of the jaw B, as will be fully understood by referring to Fig. 1. In Fig. 2 this spring is shown broken off, in order that the attachment of the jaw C to jaw B may be clearly shown.

If it should be desired to economize in the construction of the wrench, the jaws may be of iron and steel fitted in their face sides, in order to prevent the wear or abrasion thereof.

The operation will be readily understood.

The implement is adjusted to its work by the operator raising the front and disengaged end of the jaw with his thumb, so that the article to be turned may fit in between it and the face of jaw B, and by then turning the handle or lever A from right to left, as indicated by the arrow 1, the two jaws will firmly grip the article and turn it. The angle e of the jaw C forms the outer bearing for the article, while the lower jaw forms the inner bearing. The more power that is applied to the handle or lever A in turning it the greater the pressure of the jaws on the article. The hook form of the jaw C effectually prevents the escape of the article from between the jaws during the backward movement of the implement for a fresh hold or grip, the jaw C releasing the article during said movement.

The spring D is an advantage, as it renders the application of the jaw C to its work rather quicker than it otherwise would be; but still it could be dispensed with without materially detracting from the value of the implement.

The advantage that this wrench possesses over all others that have passed under my observation is that it will adjust itself to its work and to articles of different thicknesses or diameter without any special manipulation on the part of the operator, and in consequence of the jaw C being arranged relatively with the jaw B, as shown, a very strong wrench is obtained, as the pivot d of the jaw C is not subjected to much strain, and a sliding jaw, or one which requires adjustment and which is liable to get out of repair or become deranged by use, dispensed with.

I do not claim separately a jaw of hook form, for such has been used in pipe-wrenches; but

I do claim as new and desire to secure by Letters Patent—

1. The jaw C, of hook form, when attached to the jaw B and arranged relatively therewith, to operate as and for the purpose herein set forth.

2. The spring D, in combination with the jaws B C, arranged as and for the purpose specified.

H. V. FARIES.
